UNITED STATES PATENT OFFICE.

JOHN ROGERS, OF NEW CANAAN, CONNECTICUT.

DESIGN FOR A GROUP OF STATUARY.

SPECIFICATION forming part of Design No. 18,734, dated November 13, 1888.

Application filed October 9, 1888. Serial No. 287,676. Term of patent 14 years.

To all whom it may concern:

Be it known that I, JOHN ROGERS, a citizen of the United States, residing at New Canaan, in the county of Fairfield and State of Connecticut, have invented and produced a new and original Design for a Group of Statuary, of which the following is a specification, reference being had to the accompanying drawing, forming part thereof.

- 10 The group is called "Politics." A gouty old gentleman is seated in a chair. His left foot is bandaged and rests on a foot-stool. His hands grasp tightly the arms of his chair, and he looks excitedly across the table at his friend, who sits in a chair opposite to him and is also excited, for he is raising a decanter with his right hand as if to smash it down on the table, and with his left hand he holds his umbrella, which he has punched through his hat on the floor. Between them is a table with doors standing open in front, showing a drawer containing decanters and bottles. A lady stands behind the table and tries to act as peace-maker by playfully holding her hand before the mouth of one of the gentlemen and her open fan before the other.

What I claim, and desire to secure by Letters Patent, is—

A design for a group of statuary, consisting of two seated gentlemen in excited controversy and a lady standing behind a table and acting as peace-maker between them, all of which is herein shown and described.

JOHN ROGERS.
